UNITED STATES PATENT OFFICE.

FRED N. TILTON, OF HARTFORD, CONNECTICUT.

STEAM-GENERATOR.

No. 895,514.

Specification of Letters Patent. Patented Aug. 11, 1908.

Application filed February 17, 1908. Serial No. 416,253.

To all whom it may concern:

Be it known that I, FRED N. TILTON, a citizen of the United States, residing at Hartford, in the county of Hartford and State 5 of Connecticut, have invented a new and useful Steam-Generator, of which the following is a specification.

This invention relates to the construction of a continuous coil tubular boiler, which, 10 while primarily designed for use as a steam generator that is particularly adapted for steam automobiles, it may also be advantageously employed as a feed water heater and as a domestic water heater.

15 The object of the invention is to provide a very simple construction whereby a continuous tube generator or heater can be easily made up in compact form so as to have a very large area of well disposed heating surface, 20 with very few joints, which joints are all beyond the range of the direct action of the fuel, which has no short bends and but few long bends, and which will freely expand and contract under temperature changes without 25 straining the tubes or the joints and connections.

This generator or heater is built of a plural number of tapering spiral coils of different diameters, each coil being formed from a continuous length of seamless tubing or pipe, 30 and being of such diameter and having its ends so bent that the several coils can be nested one within the other, and the upper end of each outer coil connected with the lower end of the next inner coil, and thereby 35 a generating chamber be produced which is continuous from the top or small end of the inner or smallest coil to the bottom or large end of the outer or largest coil, as more particularly hereinafter described and pointed out in the claims.

Figure 1 of the accompanying drawings shows a plan of a continuous tube generator which embodies the invention. Fig. 2 shows 45 an elevation of the same generator. Fig. 3 shows a diametrical section of the same. Fig. 4 shows a plan of the inner section or smallest coil. Fig. 5 shows a side elevation of the inner coil. Fig. 6 shows a side elevation of the next to the smallest coil, or that in which the inner coil is nested, when the coils are assembled for use.

The drawings show a generator or heater formed of six tapering spiral coils wound 55 from seamless tubing or pipe, *a*, *b*, *c*, *d*, *e*, *f*, and nested together, but the invention is not

limited to this number of coils; more or less coils may be omitted or added without materially changing the construction, method of connection or mode of action of the apparatus.

Each section is bent from a single piece of pipe or tubing into a continuous tapering spiral coil. These sections are the same height but of different diameters, each being 60 made of such size that the smaller can be located in the next larger and thereby a compact mass of coils produced.

The lower or larger ends of the coils have tangentially extending limbs *a'*, *b'*, *c'*, *d'*, *e'*, 70 *f'*, that terminate beyond the plane of the outer coil in upturned ends *a''*, *b''*, *c''*, *d''*, *e''*, *f''*. The upper or smaller ends of the coils have tangentially extending limbs *a'''*, *b'''*, *c'''*, *d'''*, *e'''*, *f'''*, that terminate beyond the 75 plane of the outer coil in down-turned ends *a'''', b'''', c'''', d'''', e'''', f'''''*.

When the sections are nested, the down-turned end of each coil is connected by a union or other form of pipe connection *g* with 80 the upturned end of the next smaller coil. These connections are all on the outside of the apparatus where they can be easily made and reached at any time, and where they are not exposed to the direct action of the flame 85 from the burner. Connecting the coils in this manner leaves the upturned end extending from the bottom of the largest coil free to be connected, if desired, with the engine or other apparatus to which the steam or hot 90 water is to be supplied, and leaves the out-turned end extending from the top of the smallest coil free to be connected with the pump or other source of water supply. Of course if desired, the connections could be 95 reversed, that is, the upper or smaller end of the smallest coil could be connected with the engine or other apparatus, and the lower or larger end of the largest coil could be connected with the water supply, without changing 100 the construction of the apparatus.

Bending the tube or pipe into tapering spiral coils of different diameters enables long lengths to be nested together so that the apparatus will be very compact and yet will 105 have a great area of heating surface exposed to the flames of the burner in a very efficient manner. The risers are all on the outside of the coils where neither they, nor the connections, are exposed to the direct action of the flames of the burner, and where the joints and connections can be readily made, ob-

served and repaired if they become damaged or deteriorated. There are no short bends and the coils are so disposed that there is no strain on the joints or uprights incident to 5 expansion and contraction, and furthermore, the water of necessity has to pass either from top to bottom or from bottom to top, depending upon the mode of connection, through each coil before it passes to the next 10 coil, and thus it becomes, before it reaches the end of the pipe, very hot. With this apparatus a round burner or a round fire pot can be used and a maximum amount of heat absorbed or conserved from the burning fuel, 15 whereby a small quantity of water can be rapidly, safely and economically superheated and transformed into steam under high pressure.

The invention claimed is:

20 1. A generator consisting of a plural number of tapering spiral coils nested together with the upper end of each coil connected with the lower end of the next smaller coil by a vertical pipe, whereby a continuous

generating chamber is formed, substantially 25 as specified.

2. A generator consisting of a plural number of tapering spiral coils of different diameters nested together and each coil having a tangentially extending upper and lower end 30 with the tangential upper end of each outer coil connected with the tangential lower end of the next inner coil so as to form a continuous generating chamber, substantially as 35 specified.

3. A generator consisting of a plural number of tapering spiral coils nested together and each coil having a down-turned upper end and an up-turned lower end with the down-turned upper end of each coil connected with the upturned lower end of each next smaller coil whereby a continuous generating 40 chamber is formed, substantially as specified.

FRED N. TILTON.
